UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

SEWING MACHINE FOR APPLYING BUTTON STAY STRIPS.

1,422,220.

Specification of Letters Patent.

Patented July 11, 1922.

Application filed February 3, 1920. Serial No. 356,101.

To all whom it may concern:

Be it known that I, JAMES R. MOFFATT, a citizen of the United States, residing at Chicago, in the county of Cook, State of Illinois, have invented certain new and useful Improvements in Sewing Machines for Applying Button Stay Strips, of which the following is a description, reference being had to the accompanying drawing and to the figures of reference marked thereon.

The invention relates to new and useful improvements in a sewing machine, and more particularly to a sewing machine which may be used for applying a button stay strip to a garment.

An object of the invention is to provide devices which may be manually operated for folding the finishing-off end of the button stay strip and for holding said end folded until it is stitched.

Another object of the invention is to provide a machine with devices of the above character wherein the finishing-off end of the said strip may be folded on a line diagonally 25 of the strip so as to form a pointed finished end.

A further object of the invention is to provide a machine of the above character with a cutting device which operates to first 30 sever the button stay strip from the supply, after which the severed end is folded in the manner stated.

These and other objects will in part be obvious and will in part be hereinafter more 35 fully disclosed.

In the drawings, which show by way of illustration one embodiment of the invention:

Figure 1 is a front view of a portion of a 40 sewing machine having my improvements applied thereto;

Fig. 2 is a top plan view of the work support showing the presser foot and the parts associated therewith for severing the 45 stay strip from the supply and for folding the end thereof;

Fig. 3 is a view transversely of the machine on the line 3—3 of Fig. 2;

Fig. 4 is a sectional view on the line 4—4 50 of Fig. 2;

Fig. 5 is a view showing a button stay strip as it is passed into the machine, folded longitudinally, severed, and the end thereof folded or inturned by my improvement;

Fig. 6 is a bottom side view of a portion 55

of a garment showing a stay strip stitched thereto with the end folded by my improved devices;

Fig. 7 is a sectional view on the line 7—7 of Fig. 6;

Fig. 8 is a view, partly in section and partly in plan showing the presser foot and the cutting and folding devices, said cutting and folding devices having been actuated a sufficient distance to bring about a cutting 65 of the stay strip and a partial placing of the folder finger for the stay strip;

Fig. 9 is a similar view but showing the folder finger placed and the turning finger moved so as to fold the end of the strip about 70 the folder finger;

Fig. 10 is a plan view on an enlarged scale showing the folding finger and the turning finger with the parts in position with the end of the stay strip folded:

Fig. 11 is a sectional view on the line 11—11 of Fig. 10;

Fig. 12 is a longitudinal sectional view through the folder and the cutter and showing the means for actuating the cutter;

Fig. 13 is a view longitudinally of the work support just in rear of the cutter and looking toward the front of the machine; and

Fig. 14 is a perspective view of the folder 85 for turning the edge of the garment to which the stay strip is to be secured.

It is desirable in the finishing of certain garments to stitch thereto a button stay strip which extends along the edge of the 90 garment to which the buttons are to be sewed. This button stay strip is secured to the garment by stitching the same to the garment by a line of stitching which also secures the infolded edge of the garment. 95 In order to finish off the lower edge of the button stay strip, it is desirable to fold the edge diagonally and to secure the folded edge by the line of stitching which passes along one side of the button stay strip.

The present invention is directed broadly to a combination of devices applied to a sewing machine which may be operated at will for first severing the stay strip from its supply, and then folding the finishing- 105 off end of the stay strip. This folding is brought about by means of a folding finger which is moved so as to overlie the strip and a turning finger which is moved so as to engage the end of the strip and turn the 110

same over the folding finger. When this end of the strip has been turned over the folding finger, it is held in folded position by means of a yielding plate so that the 5 turning finger and folding finger may be withdrawn and the machine operated to finish off the stitching of the button stay strip.

Referring more in detail to the drawings, as herein shown the invention is applied to a 10 sewing machine consisting of a bed plate 1 on which is mounted a work support 2. The machine is provided with an overhanging arm 3 in which a needle bar 4 reciprocates, carrying a needle 5. The needle bar is reciprocated by a needle lever 6. The material 15 is held on the work support by means of a presser foot 7 and is fed across the work support by the usual feed dog 7^a. Cooperating with the needle 5 is a looper 5^a. These parts 20 are of the usual construction, and further detailed description of the sewing machine is not thought necessary.

In Figs. 6 and 7 of the drawings, there is shown a portion of a garment wherein the 25 body fabric is indicated at G. The stay strip is indicated at S. The edge of the garment is turned underneath, as indicated at g, and is stitched by a line of stitching, indicated at s. The stay strip as it is fed into the machine is 30 folded, as indicated in Fig. 5. Said strip is folded longitudinally so as to bring the edges of the strip substantially together. This leaves a folded finished edge f. This stay strip is severed, as indicated at c, and the 35 end of the strip, indicated at s' is folded over a diagonal line so that the cut edge, indicated at c' is parallel with the longitudinal free edges of the strip. This folded over edge lies between the body of the strip and the body of the garment, and the line of 40 stitching s passes through the strip and through the folded over end, thus securing the same. This forms a very neat finish, in which the free edge of the stay strip is a 45 folded edge and the strip terminates in a point which extends underneath the folded over section of the garment, indicated at g.

The fabric strip which is folded to form a stay strip is preferably wound in reel form 50 and is led into a folder 8. This folder is so constructed as to fold the strip longitudinally, turning the edges thereof rearwardly with the fold between the edges at the front. After the strip leaves the folder it is led in 55 a direction at right angles to the longitudinal axis of the folder. Said folder is formed with an extension 9, the free edge 10 of which is cut at an angle of forty-five degrees to the longitudinal axis of the folder and is 60 rounded off to provide a smooth edge over which the strip may be directed. After leaving this extension, the strip passes into a guiding recess 11, and thence on its way to the stitching mechanism. As the direction 65 of the strip is changed, the free edges of the

strip will be brought to the left hand side of the strip, while the other side of the strip is folded.

The body garment to which the button stay strip is attached is led through a folder 70 12 formed with a guiding recess 13 so shaped as to turn underneath the edge g of the body garment, and also fold said edge about the stay strip. This folder is shown in detail in Fig. 13, and it will be noted that the delivery 75 end thereof, indicated at 14, is so shaped as to bring about this folding of the edge of the body garment as the body garment passes therethrough. This is the usual form of folder and further description thereof is not 80 thought necessary.

The folder 12 is secured to the work support by means of a shank 15 through which a screw 16 passes, which screw is threaded into the work support. The shank 15 carrying the folder has a depending standard 17 and a bracket 18 is secured thereto by means of screws 19-19. This bracket also overlaps the work support at the right hand end thereof and a screw 20 passing therethrough 85 and threaded into the work support serves as an additional means for rigidly securing the bracket to the work support.

Mounted in suitable guides in the bracket 18 is a cutter 21, see Fig. 12. This cutter is 90 normally depressed by means of a spring 22. The cutter is raised by means of an oscillating sleeve 23 having a projection 24 on which the lower end of the cutter rests. This sleeve is secured to an operating shaft 25 by suitable set screws, and the operating shaft 25 is provided with an arm 26 which may be connected to a suitable treadle so that the shaft may be oscillated and thereby the cutter raised at will. This cutter crosses the 100 path of movement of the stay strip.

The guiding recess 11 is formed by a plate 27 which is secured to the bracket and spaced therefrom adjacent one end to form this guiding recess 11. This plate 27 forms a ledger 110 blade against which the cutting knife 21 forces the stay strip for cutting the same, the stay strip being led through this guiding recess 11 and beneath the plate 27.

From the above, it will be apparent that 115 the operator at will may depress the treadle, operate the actuating arm 26, and thus raise the cutter to cut the stay strip. After the end of the stay strip is cut, the cut end thereof adjacent the stitching mechanism is 120 folded.

This is accomplished by a fixed plate 28, a folding finger 29, and a turning finger 30. The fixed plate 28 has an upturned edge 31, and this plate is secured by screws 32 to the 125 bracket 18. Said strip passes over this upturned edge of the plate 28. The folding finger 29 is integral with an arm 33 which is secured to a vertical shaft 34. The vertical shaft 34 is mounted in suitable bearings 130

in the bracket 18. This shaft is so positioned and the folding finger so shaped that, when the shaft is turned, the folding finger is swung around in front of the edge 31 of the plate 28 with its folding edge 35, that is the edge over which the strip is folded, parallel with the upturned edge 31 of the plate 28. This folding finger swings around over the top of the stay strip. After the folding finger has moved over the strip and into position substantially parallel with the edge 31, it moves along said edge, approaching said edge closer and closer. At the same time that the folding finger is moved along the edge in the final movements thereof, the turning finger swings over the plate 28, and underneath the stay strip, which is held raised at its free end by this upturned edge 31, and engaging said free end turns it over the edge 35 of the folding finger 29. The turning finger 30 is pivoted at 36 to the arm 33 and is frictionally held in various positions on said arm.

When the arm 33 is at its extreme right hand position, as shown in Fig. 2, a stop 37 engages the turning finger and moves the same in a counter-clockwise direction until it comes against the stop pin 38. On the other hand, when the arm 33 is moved in the opposite direction, an extended lug 39 carried by the turning finger engages a stop 40 and causes said turning finger to be swung to the edge of the stay strip. In Fig. 8 of the drawings, the folding finger is shown as having been swung over the stay strip so as to hold the same down, and the turning finger is just coming into contact with the actuating stop 40. A further movement of the arm 33 in a counter-clockwise direction swings the turning finger to the position shown in Fig. 9, and this causes the end of the strip to be folded over in the manner above described.

The shaft 34 carrying the folding and turning fingers is shown more in detail in Fig. 3 of the drawings. This shaft 34 carries a collar 41 which is provided with an arm 42, and this arm extends between the arms of a swinging yoke 43. The yoke 43 is pivoted at 44 and has a depending lug 45 adapted to engage in a recess 46 formed in the lever 26. As this lever 26 is swung, it will swing the yoke 43, and this in turn will swing the shaft 34. A spring 47 wound around the shaft 34 and suitably secured thereto and to the bracket 18 normally operates to throw the folding finger and turning finger to the position shown in Fig. 2, that is, in inoperative position.

When the end of the stay strip is folded over, it is folded underneath the spring plate 48. Said spring plate 48 has a downwardly turned side edge 49, and this spring plate serves as a guide for directing the stay strip and also as yielding means for holding

the end folded over onto the bottom of the stay strip until it comes under the presser foot. Said yielding plate 48 is formed with a shank through which screws 50—50 pass for securing the spring plate to the bracket 18. Extending rearwardly from the bracket 18 is a guide 51 which is also secured by screws 50—50, and this serves to direct the edge of the stay strip until it is well underneath the presser foot. Said guide extends alongside of the presser foot to a point in rear of the stitching mechanism.

From the above, it will be apparent that the strip of fabric is directed into the machine, then folded intermediate its ends, and the direction of feed of the strip changed so that a folded stay strip is led in the direction of the feed underneath the presser foot. This stay strip crosses the path of a manually operated cutter which may be actuated at will for severing the stay strip, and the same manually actuated means which severs the stay strip operates a folding finger and a turning finger for turning over the end of the stay strip, after which the folding finger and turning finger are withdrawn and a spring plate serves to hold the end turned over, and the stay strip thus folded passes to the stitching mechanism and the end of the stay strip is finished. The upturned edge of the plate associated with the folding finger serves as a means for insuring the folding finger passing over the strip and the turning finger first passing underneath the end of the strip, and then over the folding finger and the body of the strip.

It is obvious that minor changes in the details of construction and the arrangement of parts may be made without departing from the spirit of the invention as set forth in the appended claims.

Having thus described the invention, what is claimed as new is:—

1. The combination with stitch forming mechanism, of means for folding a stay strip longitudinally and directing the same to the stitching mechanism, manually controlled means for severing said stay strip at right angles to its length, and manually controlled means for folding the cut edge of the stay strip diagonally of the length of the strip and for holding the end folded until stitched.

2. The combination with stitching mechanism, of means for folding and directing a stay strip to the stitching mechanism with the free edges thereof adjacent the needle, means for cutting said stay strip, and means for folding over the cut end of the stay strip on a diagonal line so as to bring the cut edges parallel with the free edges being stitched and for holding the end folded until stitched.

3. The combination with stitching mechanism, means for directing and folding

- the edge of a garment, means for directing a stay strip with one side thereof within the fold of the garment whereby said stay strip will be stitched with the folded edge of the 5 garment, means for severing said stay strip, and means for folding the end of the stay strip on a diagonal line for bringing the cut end within the folded edge of the garment whereby the said cut end will be stitched.
- 10 4. The combination with stitch forming mechanism, a folder for directing and folding the edge of a garment, means for folding and directing the free edges of a stay strip within the folded edge of the garment 15 whereby said free edges will be stitched as the edge of the garment is stitched, manually operated means for severing the stay strip, and manually operated means for folding the cut end of the stay strip so as 20 to bring said cut end parallel with the free edges of the strip and between the body of the stay strip and the body of the garment.
5. The combination with stitch forming 25 mechanism, a folder for directing and folding the edge of a garment, a folder for folding a stay strip intermediate its edges and for directing the same with the free edges within the fold of the garment, manually 30 operated means for operating a cutter for severing the stay strip at right angles to its length and for folding the cut end of the stay strip on a diagonal line for bringing the cut edges of the end between the body of the 35 stay strip and the body of the garment and parallel with the free edges of the stay strip, whereby said cut end will be stitched down.
6. The combination of means for directing a strip to a sewing machine, means for 40 cutting said strip at right angles to its length, a folding finger adapted to be swung over said strip to provide an edge over which the strip may be folded, and a turning finger adapted to turn the end of the 45 strip over said folding finger.
7. The combination of means for directing a strip to a sewing machine, means for cutting said strip at right angles to its length, a folding finger adapted to be swung 50 over said strip to provide an edge over which the strip may be folded, a turning finger adapted to turn the end of the strip over said folding finger, and means for operating said folding finger and turning finger, including devices whereby said folding finger may be first swung over the strip 55 and the turning finger operated only during the final movements of the folding finger.
- 60 8. The combination with means for directing a strip to a sewing machine, of a folding finger adapted to swing over said strip, a turning finger for folding the end of the strip over the folding finger, and a 65 yielding plate for holding the end folded after the folding finger and turning finger have been withdrawn.
9. The combination with means for directing a strip to a sewing machine, of a folding finger adapted to swing over said strip, a turning finger for folding the end of the strip over the folding finger, and a yielding plate for holding the end folded after the folding finger and turning finger have been withdrawn, said yielding plate having 70 means for guiding the strip to the stitching mechanism.
10. The combination with means for directing a strip to a sewing machine, of a folding finger adapted to swing over said strip, a turning finger for folding the end of the strip over the folding finger, and a yielding plate for holding the end folded after the folding finger and turning finger have been withdrawn, said yielding plate having 75 means for guiding the strip to the stitching mechanism.
11. The combination with means for directing a stay strip, a plate having an upturned edge over which said stay strip passes, a folding finger adapted to swing into position relative to the plate, and a turning finger adapted to turn the strip over the folding finger.
12. The combination with means for directing a stay strip, a plate having an upturned edge over which said stay strip 100 passes, a folding finger adapted to swing into position relative to the plate, a turning finger adapted to turn the strip over the folding finger, and a yielding plate under which the end of the strip is folded and 105 operating to hold the end folded when the folding finger and turning finger are withdrawn.
13. The combination with means for directing a strip, a folding finger adapted 110 to swing over said strip and over which the end of the strip may be folded, a turning finger holding the end of the strip over the folding finger, an arm carrying said folding finger, means for oscillating the 115 arm, said turning finger being mounted on said arm, and spaced stops adapted to engage the turning finger at the extremes of movement of the arm for swinging the same relative to the folding finger to fold the 120 end of the strip and for bringing said turning finger back to inoperative position.
14. The combination with means for directing a strip, a folding finger adapted to swing over said strip and over which the 125 end of the strip may be folded, a turning finger holding the end of the strip over the folding finger, an arm carrying said folding finger, means for oscillating the arm, said turning finger being mounted on 130

said arm, and spaced stops adapted to engage the turning finger at the extremes of movement of the arm for swinging the same relative to the folding finger to fold the end 5 of the strip and for bringing said turning finger back to inoperative position, a vertical shaft carrying said arm, a spring for swinging said shaft for holding the folding finger in inoperative position, and manually controlled means for oscillating the 10 shaft to move said folding finger and turning finger into operative position for folding the end of the strip.

15. The combination with means for di-

recting a strip to a sewing machine, a vertically reciprocating cutter for severing said strip at right angles to its length, a folding finger adapted to swing over said strip, a turning finger adapted to engage the severed end of the strip and turn the same over said finger, a yielding plate for holding the end folded, and manually operated means for operating said cutter to sever the strip and for operating said turning and folding fingers to fold the free end of the strip.

20 In testimony whereof, I affix my signature.

25 JAMES R. MOFFATT.
